UNITED STATES PATENT OFFICE.

DAVID SWITZER, OF MOUNT PLEASANT, MICHIGAN.

DEVICE FOR REMOVING MAINSPRINGS FROM CLOCKS.

SPECIFICATION forming part of Letters Patent No. 291,803, dated January 8, 1884.

Application filed August 28, 1883. (No model.)

To all whom it may concern:

Be it known that I, DAVID SWITZER, a citizen of the United States, residing at Mount Pleasant, in the State of Michigan, have invented certain new and useful Improvements in Devices for Removing Mainsprings from Clock Mechanism, of which the following is a specification, reference being had therein to the accompanying drawings.

10 This invention has relation to improvements in devices for removing mainsprings from clock-work without impairing the usefulness of any of its parts or interfering with its mechanism; and it consists in the construction and 15 novel arrangement of parts hereinafter set forth.

The invention has for its object to provide a cheap and simple means whereby mainsprings may be quickly removed from clock 20 mechanism without necessitating the operation of removing the frame and many of its parts. This object is accomplished by the devices shown and illustrated in the accompanying drawings, in which—

25 Figure 1 is a representation of sufficient of the upper and lower plates of a clock to show a mainspring and my improvements applied. Fig. 2 is a view of the mainspring with the key-arbor and post-sleeve attached, and the 30 ring applied to the spring in a wound position. Fig. 3 is a view of the plates with one post and the removable securing-plate, and Fig. 4 is a view of the spring holding ring.

Referring to the drawings by letter, A indicates the upper and B the lower plates, which 35 are connected and held apart at one end by the ordinary post, *a*, as shown. The lower plate, B, may be provided with a perforation, *b*, into which is pivotally seated the lower end 40 of the key-arbor C, which carries the mainspring. The upper plate, A, directly above the perforation in the lower plate, is provided with a notch or opening, *c*, and at opposite sides of said opening are perforations *d*.

45 D represents the arbor-securing plate, which is perforated, as shown at *e*, to receive the upper end of the said arbor when seated in the notch *c* of the upper plate, and perforated at *f* to register with those in the plate A, to re-

ceive screws or other suitable fastening devices. In some clock-work it is desirable to construct the plates of stout material and deeply seat the arbors in their pivotal bearings. In such cases the lower plate, instead of being perforated, as shown, may be notched and provided with a keeper or securing-plate similar to that of the upper plate without departing from the spirit of my invention.

50 Another important feature of my invention is the employment of a sleeve, to which one end of the mainspring is connected. This sleeve E is designed to hold the outer end of the spring, and, in connection with a bolt or rod, F, support and hold the upper and lower plates apart by the ends of the sleeve engaging the 55 inner side of the plates A and B, respectively, when stayed by the said bolt.

50 Instead of the keeper being perforated to receive the arbor, it may be notched to form a part of the bearing, and pivoted or hinged at one end to the plate, so that it may be swung around in removing and replacing the spring, the opposite end being secured by means of a small screw or other suitable fastening devices.

Having thus described my invention, what 75 I claim as new, and desire to secure by Letters Patent, is—

1. A mainspring having its outer end secured to a sleeve adapted to be held between the upper and lower plates of a clock-mechanism frame by means of a bolt or rod, substantially as and for the purpose specified.

2. The combination, with the lower plate, B, provided with means to seat the arbor carrying the mainspring, of the upper plate, A, 85 provided with means to receive and hold the upper end of the said arbor, and the spring, having its outer end secured to the tube or sleeve, which is held between the upper and lower plates by a bolt or rod passing through 90 its bore, substantially as specified.

In testimony whereof I affix my signature in presence of two witnesses.

DAVID SWITZER.
